UNITED STATES PATENT OFFICE.

CHAUNCEY SHORMAN, OF CHICAGO, ILLINOIS.

DEHYDRATING APPARATUS.

1,324,073.

Specification of Letters Patent.

Patented Dec. 9, 1919.

Application filed June 18, 1915. Serial No. 34,919.

To all whom it may concern:

Be it known that I, CHAUNCEY SHORMAN, a citizen of the United States, residing at Chicago, in the county of Cook and State 5 of Illinois, have invented certain new and useful Improvements in Dehydrating Apparatus, of which the following is a specification.

This invention relates to improvements in 10 dehydrating apparatus, and has for its object to provide a dehydrator in which the dehydrating air or other gas may be readily and efficiently distributed among the materials or food stuffs being treated.

15 Still another object is to provide in such apparatus, a rotatable air distributing member, together with means to rotate the same.

Still another object is to provide a rotatable distributing member operated by a 20 rotatable motor, in turn operable by dehydrating air or gas which is used to treat the products to be dehydrated, the air or gas used for the operation of the motor being also utilized for dehydrating.

25 Still another object is to provide a new and improved form of tray and tray supporting framework, together with means for mounting the same in the dehydrating chamber.

30 A further object is to provide a new and improved door having a plurality of locking means simultaneously operable.

These and other objects will be more fully 35 set forth and described in the following specification and shown in the accompanying drawings, in which—

Figure 1 is a side elevation of my dehydrating apparatus;

Fig. 2 is a horizontal sectional view, a portion thereof being taken along the line 2^a—2^a of Fig. 3; another portion being taken along the line 2^b—2^b of Fig. 3; another portion being taken along line 2^c—2^c of Fig. 3, and the remainder along the line 2^d—2^d of 45 Fig. 3.

Fig. 3 is a side elevation of the dehydrating shell showing a portion thereof broken away;

Fig. 4 is a vertical section of a detail of 50 the fan construction;

Fig. 5 is a side elevation of a portion of the air distributing tube;

Fig. 6 is a transverse horizontal section of the same; and

Fig. 7 is a perspective of one of the trays, 55 a portion of one side thereof being broken away.

Like numerals refer to like elements throughout the drawings, in which 10 designates generally my complete dehydrating apparatus consisting of a fan 11, a condenser 12, a heater 13, and the dehydrator proper or the dehydrating chamber 14. A supply tube or duct 15 leads from the fan 11 to the member 12, therefrom to the member 13, and therefrom through the portion 15^a to the vertical inlet pipe 15^b which communicates through the top 14^a of the shell 14 with the interior thereof. This supply tube 15^b is continued upwardly of its junction with the portion 15^a, as indicated by numeral 15^c. A fan motor casing 16 is mounted above the pipe 15^c and therein is located the fan proper 17 consisting of the blades 17^a, mounted on the hubs 17^b, carried by shaft 17^c. The hub and shaft are supported upon the ring 17^d to which they are connected by the legs 17^e. A supporting plate 18 forming part of the casing 16, is mounted upon the top of the pipe 15^c, and is apertured, as is ring 17^d, to furnish an outlet from the fan casing. A ball race 18^a is provided in the plate 18 and ball-bearings 19 are located thereon, serving to support the ring 17^d. From the elbow 15^a 85 of pipe 15 leads a pipe 20 having a valve 21 therein, this pipe leading to the inlet opening of the fan casing 16. This pipe is intended to furnish a supply of air from the pipe 15^a, under pressure, to the motor casing 16, to operate the blades 17^a after which such air, which forms a part of the dehydrating gas, is conveyed through pipe portions 15^c—15^b, to the interior of the dehydrating shell. To insure the proper operation of this motor and supplying of air thereto, I provide the valve casing 22 in the pipe 15^a, between the portion 15^b and the elbow 15^a. In this valve casing 22 is mounted a well-known form of valve, not 90 shown, the stem 23 of which projects upwardly from the casing 22 against the lever 24 on which is slidably mounted the weight 25, so that the same may be regulated, as is well known to those skilled in the art, to 95 act as a pressure-reducing means. By this means it will be apparent that the pressure of the air flowing through pipe portion 15^b

100 act as a pressure-reducing means. By this means it will be apparent that the pressure of the air flowing through pipe portion 15^b

may be automatically reduced and maintained at such reduced pressure. In this manner it will be obvious that the fan motor will operate, owing to difference in pressure between the supply and exhaust. The dehydrator 14 is supported upon the legs 14^b, and preferably above the ground level, and an outlet pipe 27 extends from the bottom thereof back to the fan 11, the latter serving not only to supply the dehydrating air or gas to the dehydrator, but also circulating the same continually. A supporting ring 14^c is located in the shell 14 adjacent the bottom thereof. Upon this ring are mounted the rollers 14^d. Adjacent the center of the bottom of the shell 14 is located the supporting plate 14^e mounted upon the supporting legs 14^f, see Fig. 3. In the top of this plate 14^e are provided a plurality of ball races for a purpose to be hereinafter described. A tray supporting framework, generally indicated by numeral 30, is located in the shell. This framework consists of a bottom peripheral ring 30^a mounted upon the rollers 14^d. Extending upwardly from this ring 30^a are the uprights 30^b, and at the top thereof is the top angle ring 30^c. A second smaller concentric bottom ring 30^d is provided, the same being mounted upon ball bearings 31 carried on plate 14^e. Uprights 30^e extend upwardly from the ring 30^d, and cross braces 30^f extend between the pairs of uprights 30^b and 30^e, as is clearly shown in Fig. 2. These cross braces consist of angle bars, each having a web adjacent and in contact, being slightly separated to permit the insertion of the uprights 30^b and 30^e. Circular tie-bars 30^g are provided adjacent the outer periphery of the framework and similar inner circular tie-bars 30^h are also provided. Baffle plates or spreaders 30ⁱ extend between and are attached to the braces 30^f, see Fig. 2. This construction provides a central space in the framework 30 and in this space is mounted the air distributing tube 32, see Fig. 5, for example. This tube is provided with rows of peripheral slots or apertures 32^a, the apertures of each row being staggered with respect to those of the adjacent rows, as is clearly shown in Fig. 5. A shaft 34 is centrally located in the tube 32 and is operatively connected to shaft 17^c of the fan motor 17. The shaft 34 is secured by cross pins 34^a to the tube 32, the latter being closed by the plate 35 at its lower end, this plate resting upon ball bearings 36 supported upon the plate 14^e, see Fig. 3.

I provide removable trays, generally indicated by numeral 40, the same being of a sector shape and arranged to fit upon adjacent pairs of braces 30^f, as indicated in Fig. 2. These trays are constructed with the sides 40^a and 40^b, being open at their

inner end, as indicated by numeral 40^c. The bottom 40^d of the trays is foraminous, or constructed of screen, to permit thorough circulation of the dehydrating gas.

The shell 14 of the dehydrator is provided with the opening 14^f, around which is mounted the flange or casing 14^s. The latter is provided with the sockets 14^t at its sides and bottom, as is shown in Figs. 1 and 3. At its top are provided the undercut or slotted lugs 14^u. A door 45 is provided, and the same is hinged at 45^a to one side of the casing 14^s, see Fig. 1. This door is provided with a plurality of slideable locking bolts 45^b at the sides thereof, these locking bolts being slideable in the straps 45^c, and preferably beveled or wedge-shaped to insure a tight fit of the door. Other straps 45^d are provided, preferably along the center line of the door and in these straps is reciprocably mounted a common locking bar 46 having a reduced lower end 46^a and an enlarged head 46^b at its upper end. Toggle links 47 extend from the locking bar 46 to the sliding bolts 45^b and a rack 46^d is provided on the locking bar 46. A rotatable gear 48 meshes with the rack 46^d and is arranged for rotation by the handle 49, the action being as follows:

When the gear is rotated in a clockwise direction, as viewed in Fig. 1, the bar 46 will be raised and the door unlocked. In reversing this operation the bar 46 will be lowered and the locking bolts 45^b will fit in the sockets 14^t while the reduced end 46^a of the bar 46 will enter socket 14^t and the head 46^b of the bar will slide beneath the lugs 14^u. By this construction it will be apparent that I lock my door at a number of points simultaneously, at the top, sides and bottom. This is a great advantage in a device of this nature where dehydrating gas is supplied under pressure, since it insures a secure fit and tight locking of the door at all points.

The apertures 32^a of the tube 32 are so located as to aline with the open ends 40^c of the respective rows of trays.

In the operation of my device air is supplied through the pipe 15^a and portion 15^b to the distributing tube 32. At the same time sufficient air is supplied through pipe 20 to operate the fan motor 17, and the shaft 34 is rotated, thus operating to rotate the tube 32. The air from the fan motor 17 exhausts through the tube 15^c, also into the distributing tube 32. As trays of food or material become sufficiently treated they may be extracted, one vertical series at a time, through the opening 14^f. Fresh trays may be inserted and the framework 30 rotated to bring another vertical row of trays into alinement with the opening 14^f. To provide for this rotation of the framework 30, I provide sockets 30^a in the

ring 30^a, in which may be inserted a bar or similar instrument, through the opening 14^c.

It will be obvious that I have provided a new and improved structure and that my invention is susceptible of many modifications and improvements, and I do not wish to be restricted to the form shown or described beyond the scope of the appended claims.

10. What I claim is:

1. In apparatus of the class described, a dehydrating chamber, means to supply dehydrated gas thereto, rotatable means to distribute said gas in said chamber, and means to rotate said last-named means comprising a motor, said motor being operable by gas supplied from said first-named means.

2. In apparatus of the class described, a dehydrating chamber, a rotatable member therein, means to supply air to said member, means to rotate said member, said means comprising a rotatable motor, and means to supply air from said air supply to said motor to operate the same.

3. In apparatus of the class described, a dehydrating chamber comprising a shell, tray supporting means mounted in said shell, means to supply dehydrating air or the like to said chamber, means to circulate said air in said chamber, said means comprising a rotatable tube, and means to rotate said tube by the supply of air thereto.

4. In apparatus of the class described, a dehydrating chamber comprising a shell, tray supporting means mounted in said shell, means to supply dehydrating air or the like to said chamber, means to circulate said air in said chamber, said means comprising a centrally located tube, and means for discharging the air from said chamber at a point opposite to that of its supply.

5. In apparatus of the class described, a dehydrating chamber comprising a shell, tray supporting means mounted in said shell, means to supply dehydrating air or the like to said chamber, means to circulate said air in said chamber, said means comprising a rotatable tube, said tube being provided with peripheral rows of apertures, and means to rotate said tube by the supply of air thereto.

6. In apparatus of the class described, a dehydrating chamber comprising a shell, tray supporting means mounted in said shell, means to supply dehydrating air or the like to said chamber, and means to circulate said air in said chamber, said means comprising a rotatable tube, said tube being provided with peripheral rows of apertures, the apertures in one row being staggered with respect to the adjacent rows.

7. In an apparatus of the class described, a dehydrating chamber, means to support materials to be dried in said chamber, and

an air distributing member mounted in said chamber, said member being provided with apertures arranged to permit circulation among said material supporting means, and means operable by the incoming air to rotate 70 said distributing means.

8. In apparatus of the class described, a dehydrating chamber, trays mounted in said chamber, and a rotatable air distributing member mounted in said chamber, said member being provided with apertures alining with and arranged to circulate air among said trays, and means to rotate said tube by the admission of the air thereto.

9. In an apparatus of the class described, the combination with a dehydrating chamber, of means for supporting within said chamber the materials to be dehydrated, air distributing means extending within said chamber, and means for rotating said distributing means relatively to the materials to be dehydrated.

10. In an apparatus of the class described, the combination with a substantially cylindrical dehydrating chamber, of means for 90 removably supporting the materials to be dehydrated within said chamber, an air distributing conduit extending within said chamber and having spaced air discharge apertures, and means for rotating said conduit relatively to the materials to be dehydrated.

11. In apparatus of the class described, a dehydrating chamber comprising a shell, tray supporting means rotatably mounted in 100 said shell, trays slidably carried by said means, said trays each being provided with an open end, and an apertured distributing tube mounted in said shell to rotate relatively to and to circulate air through said 105 open ends of said trays.

12. In apparatus of the class described, a dehydrating chamber comprising a shell, tray supporting means rotatably mounted in said shell, trays slidably carried by said means, said trays each being provided with an open end, and an apertured distributing tube mounted in said shell to rotate relatively to and to circulate air through said 110 open ends of said trays, said trays being 115 open at their tops and provided with foraminous bottoms.

13. In apparatus of the class described, a dehydrating chamber comprising a shell, a supporting plate carried adjacent the bottom of said shell, a rotatable tube mounted in said shell and supported upon said plate, and means to rotate said tube.

14. In apparatus of the class described, a dehydrating chamber comprising a shell, 125 a supporting plate carried adjacent the bottom of said shell, a rotatable tube mounted in said shell and supported upon said plate, and means to rotate said tube, said means comprising a shaft attached to said tube and 130

a motor, said shaft being rotatable by said motor.

15. In apparatus of the class described, a dehydrating chamber comprising a shell, a tray supporting frame rotatably mounted in said shell, a supporting ring carried by said shell, rollers carried by said ring, said frame being rotatably mounted on said rollers, and a supporting plate also carried by said frame, said frame also being rotatably supported upon said plate.

16. In apparatus of the class described, a dehydrating chamber comprising a shell, a tray supporting framework located in said shell, said framework comprising spaced uprights, braces extending between said uprights and attached thereto, circular tie-bars extending between said uprights, and gusset plates extending between adjacent braces 20 and attached thereto.

17. In apparatus of the class described, a dehydrating chamber comprising a shell, a tray supporting framework located in said shell, said framework comprising spaced uprights, braces extending between said uprights and attached thereto, circular tie-bars extending between said uprights, and gusset plates extending between adjacent braces 25 and attached thereto, said framework being 30 rotatably mounted in said shell.

18. In apparatus of the class described, a dehydrating chamber, a conduit arranged

to supply air or the like thereto, a pressure reducing valve located in said conduit, an air distributing member located in said shell and 35 communicating with said conduit, means to rotate said member, said means comprising a rotatable air operated motor, and means to supply air to said motor, said last-named means comprising a conduit leading from 40 said main air supply tube outwardly of said pressure reducing valve.

19. In apparatus of the class described, a dehydrating chamber, a conduit arranged to supply air or the like thereto, a pressure reducing valve located in said conduit, an air distributing member located in said shell and communicating with said conduit, means to rotate said member, said means comprising a rotatable air operated motor, 45 and means to supply air to said motor, said last-named means comprising a conduit leading from said main air supply tube outwardly of said pressure reducing valve, said motor being provided with a discharge outlet 50 communicating with said air supply pipe on the opposite side of said valve.

In testimony whereof, I have subscribed my name.

CHAUNCEY SHORMAN.
